F. O. CONILL

RAZOR CONSTRUCTION

Filed Nov. 18, 1922

Fernay O. Couill Inventor

By his Attorney Robert S. Blair.

UNITED STATES PATENT OFFICE.

FERNAN O. CONILL, OF MARSEILLE, FRANCE.

RAZOR CONSTRUCTION.

Application filed November 18, 1922. Serial No. 601,695.

To all whom it may concern:

Be it known that I, FERNAN O. CONILL, a citizen of the Republic of Cuba, and a resident of Marseille, France, have invented an

5 Improvement in Razor Construction, of which the following is a specification.

This invention relates to razor construction and more particularly to safety razor construction.

10 One of the objects of this invention is to provide a simple and practical safety razor construction that will be of efficient and highly effective action when in use. Another object is to provide a durable and rugged,

15 yet light, razor construction in which the cutting action of the blade due to a movement of translation or due to the drawing thereof in a direction substantially transversely to the direction of the cutting edge 20 of the blade is effectively combined with the cutting action resulting from a movement of the blade in a direction substantially coincident with that of its cutting edge without impairing the flexibility of

25 adjustment, convenience and precision of manipulation and ready accessibility of the parts for cleansing. Another object is to provide in a construction of the above character a practical and reliable, as well as

30 simple, arrangement for giving the blade a reciprocating movement in the direction of its cutting edge without detrimentally affecting the adjustment of the blade or its associated parts and without encumbering 35 the construction and manipulation of the safety razor. Other objects will be in part obvious or in part pointed out hereinafter.

The invention accordingly consists in the features of construction, combinations of 40 elements and arrangements of parts as exemplified in the structure to be hereinafter set forth and the scope of the application of which will be indicated in the following claims.

45 In the accompanying drawings in which are shown several of various possible embodiments of this invention and in which similar reference characters refer to similar parts throughout the several views,

50 Figure 1 is a side elevation showing one form of safety razor construction in assembled relation;

Figure 2 is a vertical cross section taken on the line 2—2 of Fig. 1;

55 Figure 3 shows an end view and a bottom

plan view of a detached adjusting member;

Figure 4 is a top plan view of a supporting and guiding member with certain of the parts associated therewith removed;

Figure 5 is a bottom plan view of a guard plate;

Figure 6 is a plan view of a double-edged cutting blade;

Figure 7 is a side elevation similar to that of Fig. 1 but showing a modified form of construction; and

Figure 8 is a vertical section taken on the line 8—8 of Fig. 7.

Referring now to the drawings and more particularly to Figs. 1 and 2, I have shown 70 a main handle portion 10 preferably of elongated cylindrical form adapted to form a convenient gripping member for the hand. The handle member 10 is preferably hollow for purposes hereinafter more clearly described, and at its upper end has rigidly secured thereto a supporting member 11 in the form of an elongated plate and associated with the handle member 10 so that its plane 75 extends substantially transversely to the axis of the handle.

A supporting member 11 is provided with a longitudinally extending rectangularly shaped groove 12 (more clearly shown in Fig. 1) adapted to form a guiding way for 85 slidably supporting the guard plate 13, the under side of which is formed to fit within the guiding way or groove 12. Thus the guard plate 13 may be moved longitudinally with respect to the supporting member 11, 90 and it will be seen that the ample coaxing guiding surfaces provided by the guiding way 12 afford not only a rigid supporting of the guard plate 13 with respect to the member 11, but also insure an accurate guiding thereof during the relative movements that take place therebetween, as will be more clearly hereinafter set forth.

In order to hold the guard plate 13 in sliding relation with the supporting member 100 11, the latter member is provided with longitudinally extending slots 14 and 15, more clearly shown in Fig. 4, and one on each side of the handle member 10, through which extend the detachable attaching members 16 105 and 17, respectively. The members 16 and 17 are rigidly mounted upon guard plate 13 and are preferably detachable with respect thereto. For this latter purpose the members 16 and 17 are conveniently provided 110

with threaded portions 16^a and 17^a respectively, threaded into the guard plate 13, and as will be more clearly seen from Fig. 2 the attaching members 16 and 17 are provided 5 with enlarged shoulder portions 16^b and 17^b respectively adapted to fit preferably snugly within the slots 14 and 15 respectively and slidable therein. The shoulder portions 16^b and 17^b may thus conveniently 10 coat with the longitudinally extending slots 14 and 15 respectively to assist in guiding the guard plate 13 throughout its movements with respect to the supporting member 11. The outer portions of the attaching members 16 and 17, as indicated at 15 16^c and 17^c respectively, are preferably of still greater diameter so as to overlap the under side of the supporting member 11 and thus securely hold the guard plate in its 20 slidable relation to the supporting member 11. Moreover, it will be seen that upon removal of the attaching members 16 and 17 by unscrewing them from the guard plate 13, the latter with its associated parts may 25 be readily removed.

Referring now to Fig. 5, it will be seen that the guard plate 13 is provided at its opposite side edges with a series of spaced, integrally formed members, generally indicated at 18, with which the cutting blade is 30 adapted to coat. Referring now to Fig. 1, it will be seen that the upper face of the guard plate 13 is substantially plane-faced, as at 19, throughout a substantial extent laterally so as to provide the projecting blade-supporting edges 13^a and 13^b respectively, it being noted that the spaced members 18 are 35 inclined inwardly in a direction toward the supporting member 11. A blade member 40 20, preferably of thin steel and somewhat flexible and provided also with two oppositely disposed cutting edges 20^a, 20^b (see Fig. 6) is adapted to be mounted upon the plane-faced side of the guard plate 13 so 45 that the cutting edges 20^a and 20^b substantially overlap the supporting edges 13^a and 13^b, respectively. The cutting blade 20 is 50 preferably adjustably secured with respect to the guard plate 13.

55 Referring now to Fig. 2, it will be seen that the guard plate 13 is provided with a substantially centrally positioned and upwardly extending threaded stud 21, the stud 21 passing through a centrally positioned opening 20^c in the blade 20 (see Fig. 6). After the blade 20 has thus been positioned upon the plane-faced side of the plate 13 with the stud 21 extending through the opening 20^c, a blade-holding plate 22 is 60 thereupon placed over the blade 20 in order to securely position the blade 20 with respect to the guard plate 13. For this purpose the blade-clamping plate 22 is provided with two inwardly directed studs 23 and 24 preferably integrally formed therewith and

adapted to pass through suitably spaced openings 23^a and 24^a in the blade 20. The studs 23 and 24, moreover, are adapted to enter suitably formed and aligned recesses 23^b and 24^b, respectively, in the guard plate 70 13, thus aligning the clamping plate 22, as well as the blade 20, with respect to the guard plate 13. A thumb nut 25 is rotatably mounted as by means of the shoulder 75 26 within the central portion of the clamping plate 22 and is adapted to be placed in threaded engagement with the threaded stud 21 in order to adjust the clamping plate 22 toward or away from the guard plate 13.

As shown in Fig. 3, the guard plate 22 is 80 curved transversely to its longitudinal axis, and its opposite longitudinal edges, referring now to Fig. 1, are adapted to engage the outer edge portions 20^a and 20^b of the blade 20 which overlap the blade-supporting edges 85 13^a and 13^b respectively of the movable guard member 13. The curved clamping plate 22 when moved toward the guard plate 13 by means of the thumb-nut 25 will cause the blade 20 to be bent much in the manner 90 as shown in Fig. 1, thus bending the cutting edges 20^a and 20^b toward the comb-shaped projections 18 of the guard plate 13. In this manner the cutting edges of the blade may be spaced from the comb-shaped portions 18 95 of the guard plate 13 to as great an extent as desired, in order thus to adjust the cutting action of the blade.

Turning now to Fig. 2 of the drawings, the handle member 10 is bored out to a uniform diameter, as at 10^a, throughout its extent to provide a suitable bearing surface for supporting a rotatable operating shaft 27. The shaft 27 is preferably of smaller diameter than the bore of the handle 10 but 100 is enlarged at its respective ends, as at 27^a and 27^b to be rotatably supported in the bearing surface 10^a. At its upper end the shaft is provided with a crank disk 28^a of larger diameter than the bore 10^a of the 105 handle 10 and seated within a suitable recess 28^b in the supporting member 11. In the crank disk 28^a is a crank pin 28 eccentrically positioned with respect to the axis of the shaft 27 and projecting upwardly beyond the supporting and guiding member 11. The crank pin 28 is received within a transversely extending slot 29 substantially centrally positioned in the guard plate 13 (see Fig. 5) so that upon rotation of the shaft 27 110 the crank pin 28 will transmit to the guard plate 13 and its associated parts a reciprocating movement, thus carrying both the guard plate 13 with associated blade 20 back and forth in a direction substantially coincident with the direction of the cutting edge or edges of the blade 20.

The lower end bearing portion 27^a of the shaft 20 is suitably formed at its lower end as at 27^c for detachable engagement with the 115 120 125 130

end of a flexible shaft (not shown in the drawings) driven from any suitable source of motive power and at a suitable rate of speed. Thus the lower end of the handle 10 is hollowed out as at 10^a for the reception of the end of the flexible shaft and its sheath. It will thus be seen that by means of the handle 10 the cutting edge (either 20^a or 20^b) of the blade 20 may be given a movement 10 of translation in a direction substantially transversely to that of the cutting edge of the blade and that during such movement the blade itself, together with the guard plate 13, is given a reciprocating movement in a direction substantially coincident with that of the cutting edge that is operated. It will moreover, be seen that the blade may be readily adjusted for the desired cutting action with respect to the comb-like edge portions 18 of the guard plate 13 without disturbing or detrimentally affecting the reciprocating movement thereof and the mechanism for bringing such movement about.

As will be seen in Fig. 2, the parts may be 25 readily taken apart for cleansing purposes and that the operating shaft 27 may likewise be readily removed, it being held in place by the disc 28^a on the inside of the member 11 and, in effect, locked in position by the guard plate 13 itself, with which it is in operative engagement.

In Figs. 7 and 8 I have illustrated a modified form of apparatus in which certain of the features hereinabove described are attained in a somewhat more simplified mechanical arrangement. It will be seen, referring now to Fig. 8, that the handle 10 is bored out as at 10^e throughout substantially its entire extent, this bore being of 40 uniform diameter throughout. The operating shaft 27 is provided with a lower enlarged bearing portion 27^a and an upper enlarged bearing portion 27^b of the same diameter and is held against axial movement 45 in one direction by means of the removable screw stud 30 which is threaded into the handle 10 and against which the enlarged bearing portion 27^b of the shaft 27 abuts. At its upper end the shaft 27 is provided 50 with the crank pin 28 for engagement with the guard plate 13 to actuate the same in substantially the same manner as hereinbefore described, the guard plate 13 acting in effect also to lock the shaft 27 against axial 55 movement in an upward direction as viewed in Fig. 8.

The supporting member 11, however, is grooved longitudinally to provide a dovetailed way, generally indicated at 31, and 60 the guard plate 13 is formed at its underside with a coacting portion 32 likewise dovetailed, thus not only to slidably engage the supporting member 11 but also to be securely held in engagement therewith. 65 The mounting of the blade 20 and its ad-

justment with respect to the guard plate 13 is substantially similar to that already hereinabove described.

In assembling the modified form shown in Figs. 7 and 8, the guard plate 13 with its associated parts is first placed in slidable engagement with the dovetailed way 31 of the supporting member 11 whereupon the operating shaft 27 may be inserted in the bored-out portion 10^e of the handle 10 to place the crank pin 28 in engagement with the slot 29 in the guard plate 13. The locking screw 30 is then driven home thus not only locking the shaft 27 against displacement, but also, in so doing and acting through the shaft 27 and the crank pin 28, preventing the guard plate 13 from coming out of operative relation with the supporting and guiding member 11.

It will thus be seen that there has been provided in this invention a simple and practical razor construction in which the several objects hereinabove set forth are attained and in which many advantages are successfully achieved. It will be seen that the apparatus is of simple and rugged construction, is of convenient adjustment, and may be readily taken apart for cleansing purposes, being thus conducive to a high degree of sanitation. Moreover, it will be seen that the normal cutting action of the blade due to the movement of translation manually imparted to it is effectively supplemented and combined with the cutting action due to the reciprocating movement in a direction substantially coincident with the direction of the cutting edge, and that such combined action is attained without interference with the simple mounting and ready and convenient adjustment of the blade for most efficient use. Moreover, the construction is exceedingly light and is not impaired by complicated and cumbersome operating mechanisms, thus facilitating great convenience as well as precision of manipulation, when in use.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim as my invention:

1. In razor construction, in combination, a hollow handle member provided at one end thereof with a supporting member extending transversely thereof, said supporting member having formed therein longitudinally extending guiding ways, a guard plate slidable lengthwise with respect to said supporting member and adapted to be guided by said guiding ways, means for detachably holding said guard plate in assem-

- bled relation with respect to said guiding ways, a cutting blade associated with said guard plate and having its cutting edge extending lengthwise thereof for coaction therewith, a rotatable shaft mounted within said hollow handle member and having a detachable connection with said guard plate for producing a reciprocatory movement of said guard plate with associated blade lengthwise 5 of said guiding ways, said guard plate preventing axial movement of said shaft in one direction, and means releasably holding said shaft against axial movement in the other direction.
- 10 2. In razor construction, in combination, a handle portion provided with guiding means, a guard mounted upon said guiding means and slidable lengthwise thereon, a razor blade mounted on said guard and with 15 its cutting edge extending lengthwise thereof and movable therewith, means for adjusting the cutting edge of said blade toward or away from said guard, and means for reciprocating said guard with respect 20 to said guiding means.
3. In razor construction, in combination, supporting means having formed therein longitudinally extending guiding means, a guard plate mounted on said supporting 25 means and slidable lengthwise with respect thereto, said guiding means being adapted to guide said guard plate, a cutting blade mounted upon said guard plate with its cutting edge extending lengthwise thereof and 30 coacting therewith, means for reciprocating said guard plate with said blade mounted thereon with respect to said supporting means said guard plate being guided during its reciprocation by said guiding means,
- 35 40 and means associated with said supporting means for manually giving said supporting means with associated guard and cutting blade a movement of translation.
4. In razor construction, in combination, 45 a guard plate, a cutting blade associated therewith, said guard plate coacting with said blade to limit the cutting action thereof, means for manually giving said guard plate and associated blade a movement of
- 50 translation, means for reciprocating said guard plate with associated cutting blade during said movement of translation, and means permitting relative adjustment toward or away from one another of said 55 guard plate and the cutting edge of said blade, thereby to predetermine the limiting action of said guard plate.
5. In razor construction, in combination, 60 a guard plate, a cutting blade associated therewith and having a cutting edge aligned with said guard plate, said guard plate acting to limit the cutting action of said cutting edge, means associated with said guard plate permitting the latter with its 65 associated blade to be given a movement

of translation substantially transversely to the direction of said cutting edge, means for giving said guard plate with its associated blade a reciprocatory movement substantially in the direction of the cutting edge 70 of said blade, and means for simultaneously clamping said blade to said guard plate and for adjusting the cutting edge of the blade toward or away from said guard plate.

6. In razor construction, in combination, 75 a supporting member provided with longitudinally extending guiding ways, a guard plate formed on one side thereof to coact with said guiding ways and slidable lengthwise therein and relative to said supporting member, a cutting blade associated with said guard plate and mounted on the other side thereof with its cutting edge extending lengthwise of said guard plate, means for mounting said cutting blade upon said 80 guard plate and adapted to permit adjustment of said blade with respect to said guard plate, manual means adapted to permit said supporting member with its associated guard plate and cutting blade to 85 be given a movement of translation in a direction substantially transversely to the cutting edge of said blade, and means for reciprocating said guard plate with associated blade with respect to said guiding 90 ways in a direction substantially coincident with the cutting edge of said blade.

7. In razor construction, in combination, 95 a supporting member provided with guiding means, a guard plate mounted upon said supporting member and slidable with respect thereto within said guiding means, means for reciprocating said guard plate with respect to said supporting member, a cutting blade mounted upon said guard plate and on the side thereof remote from said supporting member, and means associated with said guard plate adapted simultaneously to clamp said blade to said guard plate and to adjust the cutting edge of said blade toward 100 or away from said guard plate.

8. In razor construction, in combination, 105 a supporting member provided with guiding means, a guard plate slidably and detachably mounted upon said supporting member and adapted to be guided by said guiding means, a cutting blade associated with said guard plate, and rotatable means associated with said supporting member and detachably connected with said guard plate 110 for reciprocating said guard plate with its associated blade with respect to said supporting member.

9. In razor construction, in combination, 115 a supporting member provided with guiding means, a guard plate slidable lengthwise upon said supporting member and adapted to be guided by said guiding means, a cutting blade associated with said guard plate having its cutting edge extend- 120

- ing lengthwise of said guard plate and co-
acting therewith, said guard plate being
provided with a slot extending substantially
transversely to the direction of said guid-
ing means, a rotatable shaft supported with
respect to said supporting member and hav-
ing a crank pin extending into said slot in
said guard plate for reciprocating the lat-
ter with its associated blade with respect to
5 said supporting member, said guard plate
preventing axial movement of said shaft in
one direction, and means holding said shaft
against axial movement in the other direc-
tion.
10. In razor construction, in combination,
a supporting member provided with guid-
ing means extending longitudinally thereof,
a guard plate slidable lengthwise with re-
spect to said supporting member and adapted
20 to be guided by said guiding means, a cut-
ting blade associated with said guard plate
having its cutting edge extending length-
wise of said guard plate and coacting there-
with, a hollow handle member secured to
25 said supporting member and extending sub-
stantially transversely thereto whereby said
guard plate with associated blade may be
given a movement of translation substan-
tially transversely to the direction of the
30 cutting edge of said blade, and rotary means
mounted within said hollow handle mem-
ber and having a connection with said guard
plate for producing a reciprocatory move-
ment of said guard plate with associated
35 blade with respect to said supporting mem-
ber and in a direction substantially coinci-
dent with the direction of the cutting edge
of said blade.
11. In razor construction, in combination,
40 a supporting member provided with guiding
means, a cutting blade associated with said
- supporting means and adapted to be slid-
ably moved with respect thereto and in a
direction lengthwise of the cutting edge of
said blade, said guiding means acting to 45
guide said cutting blade, guard means asso-
ciated with said supporting member for lim-
iting the cutting action of said blade, means
for reciprocating said blade relative to said
guiding means and means permitting rela- 50
tive adjustment between said guard means
and the cutting edge of said blade to vary
at will the limiting action of said guard
means.
12. In razor construction, in combination, 55
a supporting member having guiding means
thereon, a cutting blade, means mounting
said cutting blade upon said supporting
member adapted to permit said cutting blade
to be moved with respect to said support- 60
ing member, said mounting means being
guided by said guiding means, a hollow han-
dle member associated with said support-
ing member, a rotatable shaft mounted with-
in said handle member, said shaft being 65
provided at one end thereof with detach-
able mechanical connections with said cut-
ting blade adapted upon rotation of said
shaft to give said cutting blade a recipro-
cating movement with respect to said sup- 70
porting member and means mounting said
mounting means and said shaft relative to
said supporting means adapted to permit
relative movement therebetween in the di-
rection of the axis of said shaft to detach 75
said connections and to permit removal of
one of said mechanically connected parts.
- In testimony whereof, I have signed my
name to this specification this 16th day of
November 1922.

FERNAN O. CONILL.
